PIANO ACTION

Alexander P. Brown, Beechhurst, N. Y.

Application December 23, 1947, Serial No. 793,343

6 Claims. (Cl. 84—240)

1

This invention relates to piano actions used in vertically stringed piano.

The improvement consists in providing direct blow vertically stringed piano action with means for allowing the hammer action to be set lower in a piano case by a built up wippen construction to bring up the wippen and key lever contact surface above the level of the wippen flange pivot, and for keeping the key and wippen contact point at a minimum friction and in a mean kinetic line position of least resistance namely, a built up wippen, with the key motivating contact point substantially above the wippen flange pivot level to enable a shortening of the connecting arm of the key; in an improved construction wherein the spoon is visible from the top of the action, and in making it accessible for regulation and easy repairs, which can be visibly regulated from the top of the action, eliminating the necessity of removing the action out of the piano case in order to make the spoon regulation. The key lever and the action has no locked contact, therefore, either the action, or the keys, may be readily and easily lifted out of the piano without disturbing any of its adjustment or regulation; an improvement consisting in providing the butt of the hammer with a laterally extending shoulder to engage the spoon, which is supported by the damper lever and is substantially at right angles to the damper lever to activate the damper head; and a spring interposed between the butt and damper lever, in order to quickly move the butt so that the hammer quickly moves away from the string into its rebound position, this rapid action resulting from a stored energy in the spring transposed through the spoon on to the butt to quickly return the hammer to its rebound and rest position, thereby to eliminate the bridle wire and bridle tape; and in providing a shoulder on the wippen to limit its down movement and thus prevent the jack from dropping below the butt jack cushion, when any of the keys or the action is lifted out of the piano case.

The invention will be further described herein-after, an embodiment shown in the drawings, and the invention will be finally pointed out in the claims.

In the accompanying drawings,

Fig. 1 is a side view of a piano action embodying the invention, the full lines showing the at 50 rest position of the hammer and the dotted lines showing the rebound position;

Fig. 2 is a fragmentary side view of parts taken out of Fig. 1, corresponding to the rest position of the hammer;

2

Fig. 3 is a similar view but with the position of the parts corresponding to the moment when the hammer is striking the string; and

Fig. 4 is a detail fragmentary view with the wippen broken away, and cooperating with the piano key extension lever.

Similar characters of reference indicate corresponding parts throughout the various views.

Referring to the drawings, the rail 10 supports at one of its upper corners 11, a detachable flange 12 to which is pivoted at 13, the hammer butt 15 having the hammer shank 14. The other upper corner 16 supports a detachable flange 17 to which is pivoted at 18 a damper lever 20 having a spoon 19 secured thereto, which spoon extends generally at right angles of the damper lever 20, at least the damper lever 20 and spoon 19 form an elbow lever (Fig. 2) shown in dotted lines 20a pivoted at 18. The pivot points 13 and 18 are on the same line 18 substantially horizontal. A spring 21 is disposed between the damper lever 20 and butt 15.

The butt 15 is formed like an elbow lever shown in dot dash line 15a (Fig. 2), cooperating with the 25 aforesaid right angle or elbow lever 20a. At the other side of the pivot of the butt 15 an abutment level 25c (Fig. 2) formed by the construction of the butt 15, pivoted at 13, is acted upon by the jack 25. The normal initial position of the 30 parts described are shown in Fig. 1 in full lines, their rebound back check position corresponding to the hammer after actually striking the string being shown in Fig. 1 in dotted lines, while the finger still holds the key down, as shown in the 35 dotted line position of the keys in Fig. 1.

Fig. 3 shows the position of the parts, corresponding to that moment when the hammer is striking the string before its back check rebound (as shown in dotted lines in Fig. 1).

On the same rail 10 but at its lower end 26, a 40 detachable flange 27 supports and pivots a wippen 30, pivoted at 28. The body of the wippen 30 is built up to a contact level 29, which is substantially above the level of the flange pivot 28. The 45 wippen 30 is preferably cut out at its upper edge to form a groove 30a to accommodate the lower end of the jack 25 pivoted to the wippen 30 at 31 (Fig. 4).

Substantially at right angles to the longitudinal line of the wippen 30 and in the embodiment, extending upwardly is an abutment or shoulder 35, which, when it abuts against the flange 27 of rail 10, limits the downward movement of the wippen and of the jack 25, so that the upper 55 end of the jack 25 may not go below the butt jack

cushion felt 50, in fact the upper end should descend only about midway of the vertical side of the butt jack cushion felt 50, when the key is taken out of the piano or when the action with the rail 10 is lifted from the piano itself. This shoulder 35 on the wippen 30 obviates the need of bridle straps, since one function of a bridle strap is to control the level of the upper end of the jack, and the other function is to pull back the hammer through the action of the damper spring, 10 and the weight of the wippen. The shoulder 35 prevents the jack 25 from dropping below the butt jack cushion. In the drawings a slight space is shown between the shoulder 35 and flange 27, which allows a limited movement of the wippen 30.

A spring 32 is pivoted to the wippen 30 at 53 and is disposed between the jack 25 and the wippen 30, to control the jack.

The vertically aligned rail 10 with its hammer butt pivot 13 and its lower wippen pivot 28, has in effect two laterally extending levers, joined by 20 the vertical lever formed by the jack 25 at its pivot 31 and at butt contact on the buckskin 81. This is in the nature of a parallelogram. The key contact point 54 on the wippen is above the 25 level of the wippen flange pivot 28 with the vertical line of the jack 25 in line with the pivot 31 and said contact point 54.

Substantially parallel to the jack 25 is a back check wire 40 fixed to the end of the wippen 30 30 having its lower end supported by the free or unpivoted end of the wippen 30 and its upper end provided with a back check 41 having a buckskin layer 41a to engage the belted back stop 42 of a neck 43 of the butt 15. The buckskin layer 41a and felt 42 engage each other. This back check action prevents the hammer from striking the strings more than one time for each finger stroke on the key.

Under the old style invisible spoon action the damper lever spring exerts a pressure on to the upper portion of the damper lever, transferring this pressure to its lower portion exerting it on to the spoon, which is in the wippen, thence to the bridle wire, thence to the bridle tape, thus urges the return of the hammer. In the improved visible spoon construction the spring action is such that the lower portion of the right angle construction or this damper lever 20 with the spoon 19 reaches under the rear butt portion 45 and exerts this spring pressure directly on the butt and urges a faster hammer return; this improved construction eliminates the need of the usual bridle tape and bridle wire.

A further improvement is the construction of the key operated wippen. By the contact surface 23 in the wippen 30, the contact of the button cloth 54 with the wippen 30 is raised, and the underkey extension arm 56 supporting the button cloth 54 and supported by the key 57, is made shorter thus eliminating the objectionable flexibility of the old style. This arm 56 is secured to the rear bottom end of the key 57 by regulating screws 58, a knuckle 58a allowing for adjustment. The key 57 is pivoted on the pin 59 of the key rail 60, and seats normally on the pad 61 of the rail 62. Thus by depressing the front of the key 57, the arm 56 is raised to its dotted line position 56a.

The improved parts as described are shown combined with parts old and well known. The rail 65 has the adjustable screw 66 with its felt pad 67. The hammer shank 14 on the butt 15 supports the hammer 68 which rests against the movable hammer rail 69 with its felt pad 70, oper-

5

able by a pedal (not shown). The damper rail 71 is moved by the pedal operated vertical dowel 72. The damper 73 with its felt 74 is supported by the damper lever rod 75, and is adjustable by the screw adjustment 76.

In Fig. 2 is a diagrammatic fragmentary view of the parts corresponding to the full line position of Fig. 1, and in Fig. 3 the same parts as in Fig. 2 are shown corresponding to the position of the parts when the hammer is in striking contact with the string 77.

In Fig. 2, the vertical or long part 21c of the spring 21 has a heavy pressure which regulates the hammer with a light pressure, and the horizontal or short part 21a of the spring 21 which is pivoted to the butt 15 by a pin 55 or the like, in a suitable cutout 55a to accommodate the entrance of the arm 21a of the spring, has light pressure which regulates the damper with a heavier pressure. A convolution or turn 21b is disposed between the long arm 21a and the short arm 21a. The free end of the spring arm 21c is merely inserted into the upper portion port 21d of the damper lever 20. Thus a frictionless and squeakless spring is provided by the floating convolution.

In Fig. 2 the operating surface of the spoon 19 is slightly above the dotted kinetic line 78 with suitable space between the surface of the spoon 19 and the butt felt 80. The rest position of the mean motion of the top of the jack 25 contacting the buckskin 81 of the butt 15 covering reinforcing felts 82, is somewhat below the dotted line 78.

In Fig. 3 corresponding to the hammer touching the string, the operating surface of the spoon is slightly below the said line 78, with no space between spoon 19 and felt 80. The top of jack 25 is out of contact with the butt and is somewhat above the line 78. The butt buckskin 81 is above the line. It will be noted that when in string contact position of Fig. 3, the hammer shank 14 and the damper lever 20 are generally parallel with each other (Fig. 3) with the top of the rail 10 as a base in contrast to the divergent rest position shown in Fig. 2. Thus, the spoon 19 on the damper lever 20 under the control of the operator's depressed finger storing up the energy in the convolution 21b of the spring 21, the parts take the position shown in Fig. 3 momentarily. The hammer 68 then rebounds to the dotted line back checked position of Fig. 1. When the performer's finger releases the key the stored up energy acts upon the damper lever and its spoon and quickly returns the hammer 68 from the dotted line position shown in Fig. 1 to its full line rest position.

The novelty is (a) the built up contact level 29 of the wippen 30 to raise the contact felt 54 with the underkey rocker extension lever arm 56 to shorten the key arm, the contact point being above the level of the pivot of the wippen flange; (b) the spoon visible and regulated from the top of the action; (c) the butt damper activating shoulder foot 45 on butt 15 which acts upon the visible spoon 19 at right angles to the damper lever 20, storing up energy in the spring 21; and (d) the shoulder 35 on the wippen 30 to limit the movement of the wippen 30 and to prevent the jack 25 from dropping below the butt jack cushion.

Certain subject matter is being claimed in a divisional application filed June 2, 1949, under Serial No. 96,794.

I wish to be understood that I do not desire to be limited to the exact details of construction

shown and described, for obvious modifications will occur to a person skilled in the art.

I claim:

1. In a piano action, an action rail, flanges on the upper portion of the rail, a hammer butt pivoted to one of said flanges, said butt having a rear laterally extending damper activating shoulder, a damper lever pivoted to the other of said flanges, and a spoon lever on said damper lever and extending from the damper lever to the hammer butt shoulder across the top of the rail, whereby the shoulder of the butt activates the spoon and its damper lever, the said spoon being visible from the top of the action, easily accessible from above the action, and conveniently regulatable from the top of the action.

2. In a piano action the combination of hammer butt having a laterally extending shoulder, a damper lever, a spoon lever on said damper lever and extending under said butt shoulder, said spoon lever being substantially at right angles to the damper lever, and a frictionless two legged spring having a free floating junction, the legs exerting pressure on the damper lever and thus on said spoon lever transposing the spring pressure to the butt in order to quickly move the butt so that the hammer quickly moves away from the string into its rebound backcheck position, while the key is depressed, and on release of the key the said spring quickly moves the hammer to rest position.

3. In a piano action, a hammer butt, a damper lever, a spoon lever on the damper lever extending towards and in contact with the butt, and a spring disposed between the damper lever and the butt and one end acting on the butt and the other end acting on the damper lever, whereby the damper lever with the spoon transposes the spring pressure through the said spoon directly on to the butt, to facilitate a faster hammer return from its string striking position.

4. In a space saving piano action the combination of hammer butt having a laterally extending damper lever spoon activating shoulder and a back stop shoulder, a pivoted wippen, a jack actuated by the wippen for operating the butt, a back check lever on said wippen, operating on the back stop shoulder, a damper lever, a spoon lever on said damper lever and extending under said activating shoulder, said spoon lever being substantially at right angles to the damper lever, and a frictionless spring having a free floating convolution exerting pressure on the damper lever and said spoon lever transposing the spring pressure to the butt in order to quickly move

the butt so that the hammer quickly moves away from the string into its rebound backcheck position, while the key is depressed, and on release of the key the said spring quickly moves the hammer to rest position.

5. In a piano action having a hammer butt with a pivotal supporting connection, the combination of a jack the tip of which is adapted to abut and contact with a surface of said butt on one side of said pivotal connection, a damper spoon having its spoon surface adapted to abut and contact with a surface of said butt on the other side of said pivotal connection, and a damper lever supporting said damper spoon, and having a pivotal supporting connection, said butt pivotal connection and damper lever pivotal connection being disposed in one line, and at the hammer rest position of said butt, the jack tip butt contacting surface and the spoon surface being disposed on said line, and at the hammer striking position of said butt, the spoon surface butt contact surface being disposed along said line, and a spring having one end on the butt and one end on the damper lever, for returning the butt to rest position after the striking of the hammer.

6. In a piano action, the combination of a hammer butt, a back stop formed as a unit with said butt, a damper lever, a spoon lever on the damper lever extending towards and in contact with said butt, a wippen, a back check on the free end of the wire, adapted to engage the back stop on the butt, and a knee action elbow spring, one end acting on the butt and one end acting on the damper lever, whereby a bridle strap is not essential between the back stop and the back check.
